MUTE FOR TRUMPETS OR LIKE
INSTRUMENTS

Guy B. Humes, Chicago, Ill.

Application December 14, 1939, Serial No. 309,231

9 Claims. (Cl. 84—400)

This invention relates to mutes for wind instruments, such as trumpets, cornets and trombones, and one object of the invention is to provide a construction designed to produce a relatively mellow and pleasing muted tone. Another object is to provide an improved construction for producing certain special effects, and a further object is to secure the desired contour of the mute by a special construction adapted for convenient and economical manufacture. Other objects will appear as the description proceeds. The invention consists in the various features and elements of construction in combination, as herein shown and described and as indicated by the claims.

In the drawing:

Fig. 1 is a side elevation of a mute embodying this invention, with a bell of a trumpet shown in dotted outline in its operative relation to the mute.

Fig. 2 is an axial section showing internal details of construction.

Fig. 3 is a transaxial section taken as indicated at line 3—3 on Fig. 2.

Fig. 4 is a transaxial section taken as indicated at line 4—4 on Fig. 2.

Fig. 5 is a perspective view partly in section, showing the adjustable supporting plug for the mute.

Fig. 6 is a rear elevation showing a modified construction.

Fig. 7 is a rear elevation showing another modification.

The mute which is the subject of this invention is shown as a composite device, capable of various uses, but it may be understood that some of the features may be employed separately and not necessarily in the complete combination shown. As illustrated, the body portion 1 is of tapering or conical form, and is preferably composed of the fiber board or similarly flexible sheet material, bent into shape and glued at the necessary joints. At the small end of the cone, which is open, I provide a metallic reinforcing ring 2, and at the larger end the body 1 deviates from a strictly conical form in that the terminal portion 3 is of slightly enlarged diameter, and is connected with the remainder of the body by a shoulder 4, as seen in Fig. 2. This form may be secured by dipping the larger end of the conical body 1 in liquid and allowing it to swell, then inserting a metallic reinforcing ring 5, and permitting the material of the cone to shrink as it dries, with the result that the terminal portion fits tightly around the ring 5, while the adjacent

connecting portion forms the sloping shoulder 4, joining the enlargement 3 with the conical body. A convex header or end wall 6 is inserted in the enlarged portion 3 and seated against the edge 5 of the ring 5 which forms a stop shoulder for this purpose.

Within the hollow conical body 1, I provide a plurality of release tubes, preferably of metal and wrapped with rubber or fabric tape or other vibration-absorbing material 8. As shown, there are three of these tubes, 7^a, 7^b and 7^c, arranged in a cluster near the smaller end of the conical body 1 and diverging toward the end wall 6 through which they extend. Preferably, the 15 three tubes 7^a, 7^b, and 7^c are of different lengths; apparently, in this way, they serve to release a wider range of vibrations. At the smaller end of the body 1, they do not occupy the full diameter of the space, but they are rigidly positioned by 20 the engagement of their opposite ends in the wall 6. These end portions may be slightly swelled or swaged to anchor them firmly, the wrappings 8 forming shoulders abutting the inner face of the wall to cooperate in providing a rigid housing for the tubes.

The mute is designed to be held frictionally in the tapering portion of the instrument adjacent the bell substantially as indicated by the dotted outline of the instrument at A in Fig. 1. It is required that the conical body 1 be spaced away from the tapering portion A¹ of the instrument to provide a limited outlet for sound around the mute, and the body is therefore supported in position by radially extending blocks of cork or 30 like material, secured to the outer surface of the conical part 1 and contacting the inner surface of the tapered part A¹. If desired, these radially extending blocks 9 may be made integral with annular portions 10, which thus connect them in spaced relation so that the spaces between the blocks 9 afford a limited outlet for the sound waves produced in the instrument. For a purpose about to be described I may provide two rings 10 with projecting blocks 9, spaced apart 40 longitudinally on the conical body 1 with a third ring 11 disposed between them, and similarly formed with projecting blocks 12, which extend for contact with the tapering tube A¹ of the instrument. The rings 10 and blocks 9 are rigidly secured as by gluing or cementing them to the surface of the mute body 1, but the ring 11 is left free for rotative adjustment between the two rings 10 so that the passageways for air may be varied, or even closed completely by shifting the 45 block portions 12 into registration or partial reg-

istration with the spaces between the blocks 9, as seen in Fig. 5.

For improving and mellowing the muted tone of the instrument I prefer to mount on the enlarged end portion 3 of the conical body a reversely disposed bell or cup 13, which opens toward the bell of the instrument A, as seen in Fig. 1. The bell 13 is formed with a shoulder 14, intermediate its ends, and a ring 15 seated against the shoulder 14 partially closes the annular space between the bell 13 and the body 1 of the mute. This forms a resonance chamber 16, which noticeably affects the quality of the tone produced by the instrument when a mute of this type is employed. As will be noted from Fig. 1, the extreme mouth 17 of the bell 13 is of smaller diameter than the adjacent portion of the bell of the instrument so as to leave an annular space, indicated at 18, for the escape of the sound as modified by the mute. In order to secure the full effect of the resonance chamber 16, the adjustable blocks 12 will be shifted to provide the maximum passage by way of the spaces between the blocks 9.

Figs. 2 and 3 show the ring or annular partition 15 mounted in contact with the bell 13, leaving an annular clearance space at 19 between the ring and the body 1. However, if desired, the ring 15 may be proportioned to fit snugly onto the conical body 1, as shown in Fig. 6, leaving a clearance gap 20 between the outer edge of the ring 15 and the inner surface of the bell 13. And, as a further modification, Fig. 7 shows a ring 21, which is fitted snugly between the body 1 and the bell 13, so as to contact with both of said parts, and the clearance space for transmission of the vibration is then afforded by a series of apertures 22 in the ring 21, spaced at intervals around it.

To secure an entirely different effect from that produced by the bell 13, the passages around the mute body 1 may be closed entirely by shifting the ring 11 to register its blocks 12 with the spaces between the blocks 9. Then the only available passageways for the vibrating air column are afforded by the opening 2, in the end of the body 1 and the release tubes 7. These tubes, being of relatively small diameter, tend to break up and weaken the force of the tone, but permit the escape of a limited amount of sound of modified quality. To produce a so-called "wow" effect, the performer momentarily shuts off the release tubes 7 entirely, as by placing his hand over the end of the mute, and to facilitate the production of this effect I prefer to secure to the end of the mute an extension ring 23, having an inturned flange 24 which leaves a large central opening 25 in a plane spaced away slightly from the open ends of the tubes 7 in the wall 6. The performer may easily close the opening 25 with the flat of his hand placed against the flange 24; then, by suddenly removing his hand and replacing it at frequent intervals, he will easily and simply produce the desired "wow" effect.

When a plurality of release tubes is employed, as in the present structure, the provision of the flanged cap 23 enables the performer to control the open ends of the tubes more easily than if he attempted to cover them all simultaneously with his hand for the purpose of this effect; therefore, the flange 23 is shown permanently attached to the body 1 of the mute. But the bell 13 may be frictionally secured by engagement of its smaller end portion 26 on the en-

largement 3 at the end of the body 1, the ring or collar 23 serving as a stop against which the bell is lodged but from which it may be separated for removal over the small end of the mute body 1, if desired.

I claim:

1. A mute comprising a hollow body of tapered form open at the smaller end and having a transverse wall at its larger end and a plurality of release tubes of relatively small bore open at both ends, grouped together within the body near the smaller end thereof and extending divergently toward the larger end of the hollow body and through said wall, a collar mounted on the larger end of the mute and having an inturned flange spaced from the open ends of the release tubes and providing a large central opening opposite the said transverse wall of the mute.

2. A mute comprising a hollow body of tapered form adapted for insertion in the bell of a wind instrument, said mute having a reversely directed bell secured to its larger end and opening toward the smaller end of the mute with a transverse annular partition disposed intermediate the ends of the bell and partially closing the space between the hollow body and the bell but providing limited clearance for access of air to the chamber formed by the conical wall of the mute in combination with said bell and partition.

3. A mute comprising a hollow body of tapered form adapted for insertion in the bell of a wind instrument, said mute having a reversely directed bell secured to its larger end and opening toward the smaller end of the mute, said bell supporting an annular transverse partition extending toward but not into contact with the conical surface of the mute, providing clearance space between the edge of the partition and said conical body and forming a resonance chamber around the mute and within the bell.

4. A mute comprising a hollow body of tapered form adapted for insertion in the bell of a wind instrument, said mute having a reversely directed bell secured to its larger end and opening toward the smaller end of the mute, and an annular partition attached to the conical body at a point intermediate the ends of the bell extending toward but not into contact with the bell, thus affording a clearance space between its edge and the wall of the bell leading to the chamber which is enclosed by the partition, the cone and the bell.

5. A mute comprising a hollow body of tapered form with a bell secured to the larger end of said body and flaring therefrom toward the smaller end, a transverse partition partially closing the space between the bell and said body portion of the mute, and spacing blocks for supporting the smaller end in a trumpet or like instrument, said blocks extending radially from the tapered body of the mute and being spaced apart circumferentially forming passages between the mute and the instrument wall, said blocks being adjustable in circumferential extent to vary the capacity of said passages.

6. A mute comprising a hollow body of tapered form with a bell secured to the larger end of said body and flaring therefrom toward the smaller end, a transverse partition partially closing the space between the bell and said body portion of the mute, a series of spacing blocks fixed to the body of the mute and extending radially therefrom for contact with the wall of a trumpet or

like instrument, said blocks being spaced apart circumferentially affording passages for sound, and a second series of spacing blocks arranged as a unit for rotation upon the body of the mute adjacent the first series and thus adjustable for overlapping the spaces between the first series of blocks to vary the capacity of said passages.

7. A mute comprising a hollow body of tapered form open at the smaller end and having a transverse wall at its larger end, a plurality of release tubes of relatively small bore open at both ends and extending from within the hollow body through the transverse wall at the larger end, a collar extending from the larger end and supporting a transverse flange in spaced relation to said end wall, a bell secured to the larger end of said hollow body and flaring toward the smaller end, together with a transverse partition partially enclosing a space between the bell and the wall of the tapered body, and supporting blocks on the body arranged to center the mute within

the wall of a trumpet or like instrument, said blocks being spaced circumferentially from each other to form passages for sound and being adjustable in circumferential extent to close the passages thus formed between the instrument wall and the mute.

8. A mute comprising a hollow body of tapered form open at the smaller end and having a transverse wall at its larger end, and a plurality of release tubes of relatively small bore and each of a different length open at both ends and extending from within the hollow body through the transverse wall at the larger end.

9. A mute comprising a hollow body of tapered form open at the smaller end and having a transverse wall at its larger end, and a plurality of release tubes of relatively small bore open at both ends extending from said transverse wall and terminating within the body at different distances respectively from the smaller end.
